UNITED STATES PATENT OFFICE.

LUCIUS EDWARD WEAVER, OF EAST HAMPTON, CONNECTICUT, ASSIGNOR TO
THEOPHILUS KING, OF BOSTON, MASSACHUSETTS.

SEWING-MACHINE SHUTTLE.

1,326,625.

Specification of Letters Patent. Patented Dec. 30, 1919.

Application filed November 15, 1918. Serial No. 262,705.

To all whom it may concern:

Be it known that I, LUCIUS EDWARD WEAVER, a citizen of the United States, residing at East Hampton, in the county of Middlesex and State of Connecticut, have invented new and useful Improvements in Sewing-Machine Shuttles, of which the following is a specification.

This invention relates to a sewing-machine shuttle which includes a shuttle body movable in a predetermined path, and a bobbin case suitably connected with the body and adapted to contain a bobbin which is rotatable in the bobbin case.

The invention has for its object to provide a bobbin case with improved means for frictionally retarding the rotation of the bobbin therein to prevent undesirable free rotation of the bobbin and a loose accumulation of thread in the bobbin case, said means being adapted to be compactly stored in the bobbin case, without encroaching objectionably on the space occupied by the bobbin, so that the axial length of the bobbin and the thread-storing capacity thereof are not necessarily reduced in consequence of the employment of said frictional retarding means.

The invention is embodied in the improvements which I will now proceed to describe and claim.

Of the accompanying drawings forming a part of this specification,—

Figure 1 is a plan view of a bobbin case embodying the invention.

Fig. 2 is a section on line 2—2 of Fig. 1.

Fig. 3 is a sectional view of a bobbin adapted for use with the improved bobbin case.

Fig. 4 is a top plan view of a shuttle, of which the bobbin case forms a part.

Fig. 5 is a section on line 5—5 of Fig. 4.

The same reference characters indicate the same parts in all of the figures.

The bobbin case in which my invention is embodied includes a head 12 and a cylindrical wall 13, said head and wall forming a bobbin chamber which is open at one end. The case also includes a tubular post 14 attached to or formed integral with the head and coaxial with the wall 13, said post forming a bearing on which a bobbin such as that shown by Fig. 3 is adapted to rotate.

The bobbin case is detachably engaged with a shuttle body 15, in any suitable way.

As here shown, the shuttle body is of the Singer central bobbin type, and is provided with a stud 16 formed to pass through the post 14, the latter being tubular. One end of the stud 16 is provided with a groove 17, 60 adapted to be engaged by a locking slide 18 which is movable on the head 12, means being provided for yieldingly holding the slide 18 in its locking position, and for displacing the slide to permit the withdrawal 65 of the stud 16 from the post 14.

The construction thus far described is well known and in common use.

In carrying out the invention, I provide the post 14 with an enlargement 19 terminating in a shoulder 20 facing the head 12 and spaced therefrom by a portion of the post which has not been enlarged. Said enlargement is formed by brazing or otherwise securing a sleeve to a portion of the 75 periphery of the post 14 as formed heretofore.

21 represents an annular shoe movable on the portion of the post between the head 12 and shoulder 20, said shoe being preferably a flat-sided annular disk or washer, the central opening of which is formed to permit free movement of the shoe on the said portion of the post, the diameter of said opening being less than that of the enlargement 19.

22 represents a spring interposed between the head 12 and shoe 21, said spring normally holding the shoe against the shoulder 20, and permitting the displacement 90 of the shoe from its normal position by a bobbin applied to the post. The shoe 21 and the spring 22 are inserted in the bobbin case before the application of the enlargement 19 to the post 14. 95

The bobbin shown separately by Fig. 3, includes a paper cap-tube 23, and a winding 24 of thread thereon. The axial length of the bobbin is such that when the bobbin case and body are connected, as shown by 100 Fig. 5, the shoe 21 is displaced from its normal position by one end of the bobbin, so that the shoe is in yielding frictional contact with one end of the bobbin and holds the opposite end in frictional contact with a portion of the body 15. The shoe and the shuttle body, therefore, frictionally retard the rotation of the bobbin and prevent the detachment of loose coils of thread therefrom. 105

The spring 22 is preferably of combined spiral and helical form, and produced by winding the wire of which it is composed around a fixed point or center, the wire continually receding from the center, and the stress of the spring being exerted to hold its central convolution above its outer convolution. The convolutions of the spring are, therefore, adapted to bear simultaneously on the head 12 when the spring is fully compressed, so that the shoe and spring are adapted to be compactly stored in the bobbin case, and do not occupy sufficient room to require any material fraction of the bobbin.

The shoulder 20 and the margin of the opening in the shoe 21 constitute complementary stop members adapted to limit the outward movement of the shoe 21, and prevent removal of the shoe and spring from the bobbin case.

It will be seen that provision is made for conveniently assembling the parts which include the bobbin case 13, the spring 22, the shoe 21, and the enlargement or sleeve 19, in such manner as to permit a limited movement of the spring and shoe, and positively prevent their removal from the case. In practice the spring is dropped loosely to place on the case head 12, the shoe is then

dropped loosely to place on the spring, and the enlargement or sleeve 19 is finally secured rigidly to the tubular post 14.

I claim:

In a shuttle of the character stated, a bobbin case comprising a head, a cylindrical wall forming a bobbin chamber which is closed at one end by said head, and is open at the other end, and a tubular post fixed to the case head and co-axial with said wall, a spring seated on the case head, an annular shoe seated loosely on said spring, and a cylindrical sleeve rigidly attached to the post and forming a bobbin bearing and a post enlargement, the inner end of said sleeve being spaced from the case head and forming a shoe stop, the shoe being displaceable from its normal position by one end of a bobbin on said bearing, and adapted to hold the opposite end of the bobbin in frictional contact with a shuttle body with which the bobbin case is engaged, the said sleeve being adapted to be fixed to the tubular post after the insertion of the spring and shoe in the case, and to inseparably secure the shoe and spring to the case.

In testimony whereof I have affixed my signature.

LUCIUS EDWARD WEAVER.
